ABSTRACT

An exemplary embodiment provides for a secure pocket that includes a backing, an inner-lower panel coupled to the backing and an upper-outer panel flap coupled to the backing. The upper-outer panel flap overlaps a portion of a circumference of the inner-lower panel and an inner-lower panel opening is covered by the upper-outer panel flap.

SECURE POCKET

PRIORITY STATEMENT

The present application hereby claims the benefit of priority of U.S. Provisional Patent Application Ser. No. 61/234,578, filed on Aug. 17, 2009, entitled "Secure Fastener Free Pocket," and is herein incorporated by reference.

BACKGROUND

Pockets are commonplace in virtually all types of attire. Typical pockets have an un-securable opening for easy insertion and extraction of objects. Pockets may also include a flap over the opening to prevent objects from falling out. The flap may also be further secured via the addition of a zipper, fasteners, hooks and loops, etc. to secure the flap a pocket base.

While a secured flap has been in use for a long time, significant improvements in pocket security have not occurred. Due to this, new designs for secure pockets are desirable.

The foregoing examples of the related art and limitations related therewith are intended to be illustrative and not exclusive. Other limitations of the related art will become apparent to those of skill in the art upon a reading of the specification and a study of the drawings.

SUMMARY

The following embodiments and aspects thereof are described and illustrated in conjunction with systems, tools and methods which are meant to be exemplary and illustrative, not limiting in scope. In various embodiments, one or more of the above-described problems have been reduced or eliminated, while other embodiments are directed to other improvements.

The claimed embodiments provide for a pocket that includes a backing, an inner-lower panel coupled to the backing and an upper-outer panel flap coupled to the backing. The upper-outer panel flap overlaps a portion of a circumference of the inner-lower panel and an inner-lower panel opening is covered by the upper-outer panel flap.

In another implementation, the claimed embodiments also provide for a secure pocket that includes a backing, an upper-outer panel flap and an inner-lower panel coupled to the backing. The upper-outer panel flap is partly coupled to the backing and partly coupled to the inner-lower panel. Also, an inner-lower panel opening is covered by the upper-outer panel flap.

In yet another implementation, the claimed embodiments provide for a secure pocket that includes a backing, an upper-outer panel flap and an inner-lower panel coupled to the backing. The upper-outer panel flap overlaps a portion of a circumference of the inner-lower panel. Also, the upper-outer panel flap is partly coupled to the backing and partly coupled to the inner-lower panel. Furthermore, an inner-lower panel opening is covered by the upper-outer panel flap.

In addition to the exemplary aspects and embodiments described above, further aspects and embodiments will become apparent by reference to the drawings and by study of the following descriptions.

BRIEF DESCRIPTION OF THE DRAWINGS

Exemplary embodiments are illustrated in referenced figures of the drawings. It is intended that the embodiments and figures disclosed herein are to be considered illustrative rather than limiting.

2

FIGS. 1A-1B illustrate parts of a pocket, in accordance with an exemplary embodiment;

FIG. 1C illustrates the assembled parts of the pocket shown in FIGS. 1A-1B, in accordance with an exemplary embodiment;

FIG. 2 illustrates an unassembled shirt and pocket, in accordance with an exemplary embodiment;

FIGS. 3-4 illustrate example placement of the pocket on a t-shirt, in accordance with an exemplary embodiment;

FIG. 5 illustrates placement of the pocket on a backpack, in accordance with exemplary embodiment; and

FIG. 6 illustrates placement of the pocket on a jacket, in accordance with an exemplary embodiment.

DETAILED DESCRIPTION

The claimed embodiments provide for a secure, self-sealing pocket with or without the use of hardware fasteners. Once an inserted hand is removed from the pocket, a flap of the pocket closes automatically. When using pockets of the prior art, a person usually needs to be cognizant to snap or close a button. Prior art pockets also allow items to fall out if no fastener is present or if the fastener is not fastened. The claimed embodiments provide for silent operation of a securely retentive pocket without fasteners. A pocket of the claimed embodiments closes without cognizant thought through the use of over-locking, opposed concavely-shaped panels. These panels are anchored around an outside periphery of the pocket and un-sealed at their opposing concavely-shaped edges.

In reference to FIGS. 1A-1B which illustrate parts of a pocket 8 and FIG. 1C which illustrates the assembled parts of the pocket 8 shown in FIGS. 1A-1B, an upper-outer panel flap 10 is anchored to an inner-lower panel 12 and a backing 14 thus sealing a top 9 and a side 7 of the pocket 8. The upper outer panel flap 10 is also partially anchored on a portion of a bottom 15 of the pocket 8 and at a side 13 of the pocket 8. The upper-outer panel flap 10 has a concavely-shaped lower open edge 17 to create an overlap 19 opposing the inner-lower panel 12. The inner-lower panel 12 is anchored to the backing 14 on sides 7, 13 and at bottom 15. The inner-lower panel 12 has a concavely-shaped top open edge 11. The backing 14 provides a foundation for the pocket 8 to encapsulate contents without requiring the use of fasteners for the contents to be secure. While edges 11 and 17 are concavely-shaped, the claimed embodiments are not necessarily limited to a concave shape.

It will be appreciated by those of skill in the art that the phrases 'upper-outer panel flap' and 'inner-lower panel' are merely illustrative and not meant to limit various implementations of the claimed embodiments.

To create the claimed embodiments, panels may be constructed in a variety of shapes and from a variety of resilient fabrics to enable a reflexively sealing pocket on a plurality of 55 surface backings. A user of the pocket 8 may insert a hand or an object between the upper-outer panel flap 10 and the concavely-shaped lower open edge 17 thereby transversely penetrating the inner-lower panel 12 via the concavely-shaped top open edge 11. The upper-outer panel flap 10 diametrically 60 overlaps the inner-lower panel pocket 12 to provide security for the pocket 8 thereby preventing ejection of pocket contents. While edges 11 and 17 are concavely-shaped, other shapes may be utilized.

Pockets of the claimed embodiments may be constructed 65 from a variety of fabrics and materials that are waterproof, fireproof, melt-resistant, wicking, etc and combinations thereof. The pocket may be fabricated in numerous shapes

and sizes and can be deployed on a variety of different item sizes. The pocket **8** may be used inside or outside of numerous types of backing materials. The backing materials may also be, for example, waterproof, fireproof, melt-resistant, wicking, etc and combinations thereof.

Pockets may be attached to numerous types of vehicles including shirts, shorts, packets, pants, saddles, hats, etc. The pocket **8** may also further include fasteners as a method of reinforcement. Example use of the pocket **8** on a t-shirt **20**, a backpack **22** and a jacket **24** is shown in FIGS. 3-6.

While a number of exemplary aspects and embodiments have been discussed above, those of skill in the art will recognize certain modifications, permutations, additions and sub-combinations thereof. It is therefore intended that the following appended claims and claims hereafter introduced are interpreted to include all such modifications, permutations, additions and sub-combinations as are within their true spirit and scope.

What is claimed is:

1. A secure pocket comprising:
  - a backing;
  - an inner-lower panel coupled to the backing;
  - an upper-outer panel flap coupled to the backing;
  - wherein the upper-outer panel flap overlaps a portion of a circumference of the inner-lower panel;
  - wherein an inner-lower panel opening is covered by the upper-outer panel flap; and
  - wherein both ends of an upper-outer panel flap opening are each located at corresponding beginnings of upper-outer panel flap edge sections coupled to inner lower panel flap edge sections coupled to the backing.
2. The secure pocket as recited in claim 1 wherein the inner-lower panel opening is concavely-shaped.
3. The secure pocket as recited in claim 1 wherein an upper-outer panel flap opening is concavely-shaped.
4. The secure pocket as recited in claim 1 wherein the inner-lower panel opening is concavely-shaped and an upper-outer panel flap opening is concavely-shaped.
5. A secure pocket comprising:
  - a backing;

an upper-outer panel flap;
an inner-lower panel coupled to the backing;

wherein the upper-outer panel flap is partly coupled to the backing and partly coupled to the inner-lower panel;

5 wherein an inner-lower panel opening is covered by the upper-outer panel flap; and
wherein both ends of an upper-outer panel flap opening are each located at corresponding beginnings of upper-outer panel flap edge sections coupled to inner lower panel flap edge sections coupled to the backing.

10 6. The secure pocket as recited in claim 5 wherein the inner-lower panel opening is concavely-shaped.

7. The secure pocket as recited in claim 5 wherein an upper-outer panel flap opening is concavely-shaped.

15 8. The secure pocket as recited in claim 5 wherein the inner-lower panel opening is concavely-shaped and an upper-outer panel flap opening is concavely-shaped.

9. A secure pocket comprising:

- a backing;
- 20 an upper-outer panel flap;
- an inner-lower panel coupled to the backing;
- wherein the upper-outer panel flap overlaps a portion of a circumference of the inner-lower panel
- 25 wherein the upper-outer panel flap is partly coupled to the backing and partly coupled to the inner-lower panel;
- wherein an inner-lower panel opening is covered by the upper-outer panel flap;
- wherein both ends of an upper-outer panel flap opening are each located at corresponding beginnings of upper-outer panel flap edge sections coupled to inner lower panel flap edge sections coupled to the backing.

30 10. The secure pocket as recited in claim 9 wherein the inner-lower panel opening is concavely-shaped.

11. The secure pocket as recited in claim 9 wherein an upper-outer panel flap opening is concavely-shaped.

35 12. The secure pocket as recited in claim 9 wherein the inner-lower panel opening is concavely-shaped and an upper-outer panel flap opening is concavely-shaped.
